[57] CLAIM

The ornamental design for a chair, as shown and described.

DESCRIPTION

FIG. 1 is a front perspective view of a chair showing my design in the form of a recliner;

FIG. 2 is a top perspective view thereof; and

FIG. 3 is a side perspective view thereof.
The side not shown is like the side shown while the rear of the chair is plain and unornamented.

FIG. 1

FIG. 2

FIG. 3
